UNITED STATES PATENT OFFICE

116,621

DESIGN FOR A DINER

Nicholas Caracasis, Roslindale, Mass.

Application January 28, 1939, Serial No. 82,651

Term of patent 14 years

To all whom it may concern:

Be it known that I, Nicholas Caracasis, a citizen of the United States, residing at Roslindale, in the county of the Suffolk and Commonwealth of Massachusetts, have invented a new, original, and ornamental Design for a Diner, of which the following is a specification, reference being had to the accompanying drawing, forming a part thereof.

In the drawing, Fig. 1 is a side elevational

view, Fig. 2 is a plan view and Fig. 3 is an end elevational view (as seen from the right in Fig. 1) of a diner embodying my design.

The rear elevation of the diner is substantially the same in contour as the front elevation except for the omission of the stepped entrance.

I claim:

The ornamental design for a diner, substantially as shown and described.

NICHOLAS CARACASIS.
